(57) **CLAIM**

The ornamental design for a vehicle side sill, as shown and described.

DESCRIPTION

FIG. 1 is a front view of a vehicle side sill according to the present invention.

FIG. 2 is a front right perspective view of the vehicle side sill shown in FIG. 1.

FIG. 3 is a front right elevated perspective view thereof.

FIG. 4 is a rear view thereof.

FIG. 5 is a rear left perspective view thereof.

FIG. 6 is a rear left elevated perspective view thereof.

FIG. 7 is a right side view thereof.

FIG. 8 is a left side view thereof.

FIG. 9 is a top view thereof.

FIG. 10 is a bottom view thereof; and,

FIG. 11 is another front view thereof, but mounted on a vehicle to show environmental structure, the vehicle being unclaimed and shown in broken lines.
